G. Shetter,
Wood Auger.
Patented Mar. 21, 1831.

2514
Mar. 21, 1831

George Sheller, A. Citizen of the United States, Letters Patent.
The Schedule referred to in these Letters Patent, & making part of the
same, containing a description in the words of the said George
Sheller himself of his improvement in the "Serpentine Screw Auger."

Be it known that I George Sheller, of the Borough of York, in the
County of York & State of Pennsylvania, have invented a new &
useful improvement in the Auger, called the "Serpentine Screw
Auger" and that the following is a full and exact description
of the said Auger as invented by me.

This Auger differs from the common Auger and also from
the Serpentine-Screw Auger, invented by me & patented September 10th
A. D. 1829. in as much as it has a double bit, and the former has a
single bit; the shaft or stem A. and spiral or B, winding in a
serpentine manner, the nib or bit C. and common screw D. are the
same as in the original; the difference is in the additional bit E.
which makes this Auger far superior, in as much as it bores stand-
ing, easier & cuts through much better than the former.

Witnesses

George Sheller.
